UNITED STATES PATENT OFFICE.

JOSEPH W. DAWSON, OF ST. LOUIS, MISSOURI, ASSIGNOR TO BARRY-WEHMILLER MACHINERY COMPANY, A CORPORATION OF MISSOURI.

BOTTLE-WASHING MACHINE.

1,171,100.

Specification of Letters Patent.

Patented Feb. 8, 1916.

Application filed April 23, 1915. Serial No. 23,309.

To all whom it may concern:

Be it known that I, JOSEPH W. DAWSON, a citizen of the United States of America, a resident of the city of St. Louis, State of Missouri, have invented certain new and useful Improvements in Bottle-Washing Machines, of which the following is a full, clear, and exact description, reference being had to the accompanying drawings, forming a part of this specification.

My invention relates to certain improvements, particularly adapted for use in bottle washing machines, one of the objects being to economize in the manufacture of machines of this kind.

Prior to this invention very large bottle washing machines have been provided with bottle carriers including large heavy sprocket chains which travel through the water in a bottle washing tank. Since the chains are subjected to the action of the water, it has been found necessary to make them of brass, copper or other expensive material adapted to withstand the action of the water. By arranging the sprocket chains in the manner hereinafter described, and by preventing the water from splashing onto the chains, the latter may be made of iron or other inexpensive material that is not adapted to withstand the action of the water. Since the chains are very long and quite heavy, the saving effected by the use of iron, instead of brass or copper, is a quite important item in the cost of the machine, and the comparatively inexpensive chains of my machine are as efficient and durable as the more expensive chains which are subjected to the action of the water.

The invention also includes other details of construction which will be hereinafter described.

Figure I is a side elevation of a bottle washing machine, embodying the features of my invention. Fig. II is a transverse section of the machine. Fig. III is a section taken approximately on the line III-III, Fig. II.

The machine I have shown to illustrate the preferred form of my invention, comprises a large tank having side walls 1 and 2, end walls 3 and 4, a bottom wall 5, and a partition wall 6' dividing the tank into compartments A and B.

The bottle carrier comprises a pair of endless sprocket chains 6, arranged at the exterior of the tank, and fitted to idle sprocket wheels 7, 8 and 9 at the side walls of the tank. The sprocket chains are driven through the medium of drive wheels 10 fixed to a shaft 11. These sprocket chains travel through guideways G, located near the upper edge of the tank, each of said guideways being provided with side walls 12 and 13. In the structure I have shown the walls 13 are formed by the upper margins of the tank, and the walls 12 are formed by Z bars secured to the side walls of the tank. A hood 14, arranged above the tank is provided with downturned flanges 15 having their lower margins arranged between the walls 13 of the chain guideways G, Fig. II. Angular brackets 16, secured to the hood 14, rest upon the walls 12 of the guideways G so as to constitute supports for the hood.

H designates bottle holders extending across the tank and secured to the sprocket chains 6 at the exterior of the tank. Each bottle holder comprises a series of bottle receiving pockets 17 secured to a channel bar 18, and angular arms 19 extending from the ends of the bar 18 and secured to the sprocket chains 6. 20 designates funnel shaped members (Fig. III) arranged immediately below the bottle receiving pockets 17 and adapted to receive the long nozzles 21.

The bottles are introduced into the bottle holders at a point X, (left side of Fig. I) and discharged at the point X', at the right hand side of Fig. I. The bottle carrier is moved step by step by means of mechanism which will be presently described, and when the bottle carrier is at rest the nozzles 21 are inserted through funnel shaped members 20 and into the inverted bottles for the purpose of washing the inner faces of the bottles. Thereafter the nozzles 21 are withdrawn from the bottles to permit the bottle carrier to continue its intermittent movement. The inverted bottles are drained as they move toward the discharge point of the machine, and the water passing from the bottles flows into the compartments A and B.

The means for operating the bottle carrier comprises a power shaft 23, (Fig. I) a pinion 24 secured to said power shaft, a gear 25 meshing with said pinion 24, a

pinion 26 secured to gear wheel 25, a gear wheel 27 meshing with pinion 26, a shaft 28 secured to gear wheel 27 and a crank arm 29 secured to said shaft 28. The crank arm 29 is shown in Figs. I and II. The mechanism just described is driven continuously to impart an intermittent movement to transmission devices which move the bottle carrier step by step. These transmission devices include a wheel W having a series of radial slots 30 adapted to receive the crank pin 29' on the crank 29, and also having a series of arcuate faces 31 adapted to be engaged by the peripheral face of a disk 32 which is secured to the constantly rotating shaft 28. When the mechanism occupies the position shown by dotted lines in Fig. I, the crank pin 29' is arranged in one of the radial slots 30, and a portion of the slotted wheel W is located directly opposite a recess 33 in the disk 32. When the crank pin 29' passes from the radial slot in the wheel W, the peripheral face of the disk 32 engages one of the arcuate faces of the wheel W, to prevent the latter from turning. It will be noted that the wheel W is driven intermittently by the constantly rotating crank arm 29, and that this intermittent movement is transmitted through a shaft 34 to a gear wheel 35 which meshes with a larger gear wheel 36, the latter being secured to the shaft 11 which constitutes the drive shaft for the bottle carrier. The sprocket wheels 10 which drive the bottle carrier are secured to the shaft 11.

The long nozzles 21 are secured to water pipes 38 and 39 which form part of vertically movable carriages. The ends of the water pipes 39 are secured to cross heads 40, the latter being slidably fitted to vertical guide rods 41. The ends of these guide rods are fixed to brackets 42 which are fastened to the side walls of the tank. The water pipes 38 (Fig. III) are secured to cross heads 43, slidably fitted to vertical guide rods 41', the latter being fixed to brackets 42' which are secured to the side walls of the tank. Flexible water supply tubes 45 lead from the water pipes 39 to a manifold 46 secured to the tank wall 2. This manifold 46 is provided with three discharge ports to permit the discharge of water into the three flexible tubes 45, and it is provided with a single inlet port for the reception of a water supply pipe 47. The water flowing from the supply pipe 47 passes into the manifold 46, through the different flexible tubes 45, into the water pipes 39, and is discharged through the nozzles 21 that are secured to the pipes 39. The water pipes 38, located in the compartment or reservoir A, Fig. III, are connected to a manifold 46' by means of flexible tubes 45.

50 designates a fresh water supply pipe 65 secured to the manifold 46'. The fresh

water flowing from pipe 50 enters the manifold 46', flows through the flexible tubes 45', into the water pipes 38, and through the long nozzles 21 which communicate with said pipes 38.

There are three rows of nozzles 21 in the compartment or reservoir B and the bottles travel step by step, from one row of nozzles to another, so that each bottle is subjected to three washing operations in passing over the compartment B. After being washed by the water flowing from the nozzles in compartment B, the bottles are thoroughly cleansed by the clean water flowing from the nozzles 21 in compartment A. The fresh water flowing from the supply pipe 50 is conducted to the nozzles in compartment A, so that the final washing operation is effected by the clean water obtained directly from the main water supply pipe. The water discharged into the bottles at the upper end of compartment A, flows into said compartment and is afterward used for the primary washing operation which takes place at the upper end of compartment B. Each of these compartments is provided with an overflow opening 52 and a discharge pipe 53 leading from said opening. Water is drawn from the compartment A through a pipe 54 leading to a pump 55 which discharges the water into the pipe 47 leading to the manifold 46. The pump 55 may be constructed in any suitable manner, and it is preferably operated continuously to draw water from the compartment A and to force said water through pipe 47 and manifold 46 to the bottle washing device in compartment B.

As previously pointed out, the horizontal water tubes 39 in compartment B are secured to cross heads 40, the latter being slidably fitted to the guide rods 41. The pipes 39 and cross heads 40 constitute a vertically movable carriage, adapted to be raised to insert nozzles 21 into the bottles, and adapted to be lowered to permit the bottle carrier to travel over the bottle washing device. The means for raising and lowering this carriage comprises a pair of arms 56 connected to the cross heads 40 by links 57. These arms 56 are rigidly secured to a rock shaft 58 which extends across the compartment B. The arms 56 are provided with extensions 59 adapted to receive a counterweight 60 which balances the weight of the bottle washing device in compartment B. The bottle washing device in compartment A is raised and lowered through the medium of arms 56' secured to a rock shaft 58', and provided with extensions 59' which support a counterweight 60'. The rock shafts 58 and 58' extend through a side wall of the tank, and they are operated through the medium of mechanism which is shown most clearly in Fig. I. This mecha-

nism includes arms 61 fixed to the rock shafts 58 and 58', a bar 62 connecting said arms 61, and a pitman 63 connecting said bar 62 to a crank 64. This crank 64 rotates continuously so as to oscillate the arms 61 and rock shafts 58 and 58', thereby raising and lowering the bottle washing devices.

It is important to note that the sprocket chains 6, forming part of the bottle carrier, are located at the exterior of the tank, while the bottle holders are arranged between the side walls of the tank. The flanges 15 depending from the hood 14 (Fig. II) and the side walls 13 of the chain guides 15 G are arranged to form shields for preventing the water from splashing onto the sprocket chains 6. Each flange or shield 15 is located near and separated from a wall, or shield 13 to provide passageways for the angular end portions 19 of the bottle holder. By constructing and arranging the parts in this manner, the sprocket chains are protected from the water thrown by the bottle washing devices. The long heavy chains 25 may, therefore, be made of cast iron or other inexpensive material, instead of brass, copper or other expensive material which has heretofore been used in the manufacture of such chains.

I claim:—

1. A machine having a tank provided with a washing device, a carrier for moving articles past said washing device, said carrier including chains and a holder for the articles to be carried, and means for protecting said chains from the water thrown by said washing device, said means including pairs of shields forming passageways for the end portions of said holder and adapted 40 to prevent the water from splashing onto said chains.

2. A machine having a washing device, a carrier for moving articles past said washing device, said carrier including a chain, a holder for the articles to be carried and an angular arm connecting said holder to said chain; and means for protecting said chain from the water thrown by said washing device, said means including a shield for preventing the water from splashing onto said chain, and the said shield being spaced from said chain sufficiently to permit the passage of said angular arm.

3. A machine having a washing device, a carrier for moving articles to said washing device, said carrier including a pair of sprocket chains, a holder for the articles to be carried, and angular arms connecting said holder to said chains; and means for 55 protecting said chains from the water thrown by said washing device, said means including a pair of shields arranged between said chains to prevent the water from splashing onto the chains, the shields being 60 located between said angular arms and at

points near said chains and spaced from said chains sufficiently to permit the passage of said angular arms.

4. A machine comprising a bottle washing device, a carrier for moving bottles to said bottle washing device, said carrier including a pair of chains, and a bottle holder secured to said chains; and means for protecting said chains from the water thrown by said bottle washing device, said means including a pair of shields arranged between the chains and between the end portions of said bottle holder so as to prevent the water from splashing onto the chains.

5. A machine comprising a bottle washing device, a carrier for moving bottles to said bottle washing device, said carrier including a pair of sprocket chains, and a bottle holder having angular end portions which are secured to said sprocket chains; and means for protecting said sprocket chains from the water thrown by said bottle washing device, said means including two pairs of shields, the shields of each pair being separated from each other to permit the 90 passage of the angular end portions of the bottle holder.

6. A machine having a bottle washing device, a carrier for moving bottles to said bottle washing device, said carrier including a pair of chains and a bottle holder having angular end portions which are secured to said chains; and means for protecting said chains from the water thrown by said bottle washing device, said means including chain 95 passageways adapted to receive said chains and provided with side walls which constitute shields for preventing the admission of water to said passageways, and shield members arranged between and separated from 100 said side walls to permit the angular end portions of the bottle holder to travel between said shield members and said side walls.

7. A machine of the character described 110 comprising a tank, a washing device in said tank, and a carrier for moving articles to said washing device, said carrier including a holder for the articles to be carried, and a pair of chains secured to said holder, said 115 chains being located at the exterior of the tank and the holder being arranged within the tank.

8. A machine of the character described comprising a tank, a washing device in said tank, a holder for the articles to be washed adapted to travel in the upper portion of said tank, a pair of endless sprocket chains arranged at opposite sides of and located entirely without the tank and secured to the 125 opposite ends of said holder, and means for driving said endless sprocket chains.

9. A machine of the character described comprising a tank, a hood located above said tank and provided with side flanges which 130

4
lie between the side walls of the tank, a pair of sprocket chains located at the exterior of the tank, a bottle holder extending across said tank, the ends of said bottle holder being provided with angular arms which extend between the flanges of said hood and the side walls of said tank, said flanges be-

ing separated from said side walls to permit the passage of said angular arms and the said angular arms being secured to said 10 sprocket chains at the exterior of said tank, and means for operating said sprocket chains.

JOSEPH W. DAWSON.
